DOOR LOCK AND LATCH

Edwall J. Baumé, Long Beach, Calif.

Application September 25, 1936, Serial No. 102,565

6 Claims. (Cl. 292—167)

This invention relates to a novel door lock and latch, the prime object of which is to provide a novel means of retracting the bolt by a minimum amount of rotation of the knob.

Another object is to provide a door lock and latch, including a novel flexible link connecting the lock bolt finger and the knob spindle, said link acting as a camming means as well as a link for the purpose of retracting the bolt.

Still another object is to provide a novel means attachable to the knob spindle which means is pivotally connected to the flexible link whereby the flexible link is actuated to retract the bolt.

13 A feature of my invention is to provide a door lock and latch which is simple in construction, easily installed, and effective in operation.

Other objects, advantages and features of invention may appear from the accompanying drawing, the subjoined detailed description, and the appended claims.

In the drawing:

Figure 1 is a side elevation partly in section of my latch and lock in position in a door.

25 Figure 2 is a top plan view of the same, a fragment of the spindle being shown.

Figure 3 is a side elevation of the lock and latch with parts broken away to show interior construction.

30 Figure 4 is a side elevation showing the parts in partial and full retracted position.

Figure 5 is a side elevation of a modified form of latch.

35 Figure 6 is a side elevation with parts broken away to show interior construction of still another modified form of latch.

Referring more particularly to the drawing, the numeral 1 indicates a door or the like, in which my lock and latch are mounted. Two horizontal bores 2, 3 are provided in the door, these bores intersecting at right angles, the one bore 2 receiving the bolt assembly and the bore 3 receiving the spindle, as will be subsequently described.

40 My latch consists of a housing 4, preferably tubular in cross section, which housing extends inwardly from the face plate 5. The face plate is attached to the edge of the door, as shown in Fig. 1, all of which is usual and well known.

50 A rear plate 6 closes the inner end of the housing 4, and this plate is suitably attached to the housing, or, if desired, may be integrally formed therewith.

55 As shown in Figs. 1 to 3, inclusive, the bolt 7 is slidably mounted in the housing 4 and pro-

trudes thru the face plate 5. A pair of guide arms 8, 8 extends inwardly from the bolt 7 and thru the rear wall 6. Each of these arms is provided with a longitudinally extending slot 9, the purpose of which will be further described.

A coil spring 10 bears against the bolt 7 and against the rear plate 6, thereby yieldably pressing the bolt outwardly. A lock bolt finger 11 extends thru the rear wall 6 and is slidable 10 therein. The cross head 12 or T-head of the lock bolt finger extends into the slots 9 and is slidable in said slots. The cross head engages the arms 8 at the outer ends of the slots 9, and thus serves to actuate or retract the bolt 7. 15 Due to the slots 9, the bolt can retract independently of the finger 11.

A coil spring 13 serves to yieldably press the finger 11 inwardly, and also acts to hold the door knob in proper position, all of which is usual in locks of this character. A lever plate 14 is removably secured to the knob spindle 15 and the lever plate is preferably provided with a square hole thru which the spindle extends. Thus, it will be evident that the lever plate 25 will rotate with the spindle as the knob is turned by the user.

A link 16 is pivotally attached to the lever plate 14 and encircles the cross head of the lock bolt finger 11. That is, this link is preferably in the form of a strap, altho other analogous forms can be used. When the door knob is first rotated, the link 16 will be tilted, as shown in solid lines in Fig. 4. This tilting of the link causes a camming action to occur between the cross head 12 of the lock bolt finger and the rear wall 6 of the housing. This serves to retract the lock bolt finger and the bolt. On further rotation of the knob, the parts assume the position as shown in dotted lines in 40 Fig. 4, whereupon the bolt 7 is retracted to its fullest extent. This combination of a camming action and a direct pull on the lock bolt finger enables the bolt to be retracted with a minimum rotation of the knob, in either direction. 45

For locking purposes, the lever plate 14 is provided with a plurality of arcuate recesses 17, one of which is engaged by a locking tumbler 18 mounted in the door. On rotation of the tumbler, a solid portion thereof rotates into the 50 recesses 17, thus holding the lever plate against rotation and thereby locking the door.

In Fig. 5, I have shown a modified form of lever which is pivotally attached to the link 19. This consists of a threaded bolt 20 which screws 55

into the spindle 21. The action and operation of the latch is the same as previously described. The threaded bolt 20, however, enables the latch to be adjusted in the door so that less care is necessary in drilling the bore 3 with relation to the outer edge of the door.

In Fig. 6, the arms 8 on the bolt are eliminated, and in this construction the bolt 22 is formed with inwardly extending lugs 23 which are engaged by the head 24 of the lock bolt finger 25. A link 26 is employed, the same as previously described. A space within the bolt 22 enables the bolt to move relative to the head 24 of the bolt finger. Springs 27, 28 yieldably press the bolt and the bolt finger inwardly, the same as previously described.

It will be noted from examination of Fig. 4 that the link 16 has a wide bearing face which acts against the head 12. An important feature of the wide bearing face against the head 12 is that it enables the bolt to be withdrawn with a minimum amount of rotation of the knob. Since the pull of the link 16 is exerted at the outer edges, as is evidenced in Fig. 4, a slight rotation of the knob will cause a considerable retraction of the bolt. The link tilts when the knob is rotated and thus a lever arm of considerable length exerts a force against the head of the lock bolt finger, thereby retracting the bolt with a minimum rotation of the knob.

Having described my invention, I claim:

1. A door latch comprising a cylindrical housing adapted to be mounted in a door, a bolt slidably mounted in the housing, a wall closing the inner end of the housing, a bolt finger extending through said wall, said bolt finger including a cross-head on the inner end thereof, means attaching the bolt finger to the bolt, a knob spindle, a lever plate non-rotatably mounted on the spindle, a link pivotally secured at one end to the lever plate, the other end of said link loosely engaging the outer ends of the cross-head whereby tilting of said link on rotation of the lever plate will cam the bolt finger inwardly to retract the bolt.

2. A door latch comprising a housing adapted to be mounted in a door, a bolt slidably mounted in the housing, a bolt finger, means slidably coupling the bolt finger and the bolt, spring means engaging the bolt and urging said bolt outwardly, an inner wall on the housing, a second spring bearing against the wall and against the bolt finger, said finger protruding through the wall, a knob spindle, a lever non-rotatably mounted on the spindle, a link pivotally attached at one end to said lever, a cross-head on the bolt finger, said link loosely engaging the cross-head whereby said finger is retracted by the link on rotation of the spindle, said link engaging said wall and the cross-head to cam the finger inwardly as said link is tilted.

3. A door latch comprising a housing adapted

to be mounted in a door, a bolt slidably mounted in the housing, a wall closing the inner end of the housing, a bolt finger extending through said wall, means slidably attaching the bolt finger to the bolt, a T-shaped head on the inner end of the bolt finger, a knob spindle, a lever mounted on the spindle, a link pivotally attached at one end to the lever, the other end of said link loosely engaging the T-shaped head of the bolt finger, said link bearing against said wall, whereby tilting of said link in either direction will urge the bolt finger inwardly, and a direct pull of said lever further retracting the bolt finger to completely retract the bolt.

4. A door latch comprising a housing adapted to be mounted in a door, a bolt slidably mounted in the housing, a bolt finger, means connecting the bolt and bolt finger, a spring in the housing bearing against the bolt and urging said bolt outwardly, an inner wall in the housing, said finger protruding through the wall, a knob spindle, a lever non-rotatably mounted on the spindle, a link pivotally attached at one end to said lever, a cross-head on the inner end of the bolt finger, said link loosely engaging the cross-head adjacent the outer ends of said head, whereby said finger is retracted by the link on rotation of the knob spindle.

5. A door latch, including a knob spindle, a housing adapted to be mounted in a door, a bolt slidably mounted in the housing, a lever mounted on the spindle, a bolt finger, means attaching the finger to the bolt, a T-shaped head on the inner end of the finger, a link pivotally attached at one end to the lever, the other end of said link loosely engaging both of the outer ends of the T-shaped head on the finger, whereby a wide bearing is provided between the head and the link, said link retracting the bolt finger on rotation of the spindle, said link tilting on rotation of the spindle, whereby the bolt finger is moved inwardly a greater distance than the inward directional movement in a parallel plane of the pivot, which connects the link and the lever.

6. A door latch including a knob spindle, a housing adapted to be mounted in a door, a bolt slidably mounted in the housing, a spring in the housing engaging the bolt to project this bolt outwardly, a lever plate mounted on the spindle, a finger attached to the bolt, a cross-head on the finger extending outwardly from the center longitudinal axis of the finger, a link loosely engaging both of the outer ends of the cross-head, a pivot pin connecting the inner end of the link to the lever plate, said link being tilted by the rotation of the lever plate, the link bearing against the outer ends of the cross-head on rotation of the lever plate, thereby retracting the bolt a greater distance along its longitudinal axis than the travel of the pivot pin of the lever plate in a parallel plane when the knob spindle is rotated.
